one-half to Hollywood Gift and Novelty Co.
Inc., a corporation of California

Application February 22, 1945, Serial No. 118,088

Term of patent 3½ years

(Cl. D34—15)

To all whom it may concern:

Be it known that I, Alvin D. Bloom, a citizen of the United States and residing at Los Angeles, in the county of Los Angeles, State of California, have invented a new, original, and ornamental Design for Peashooter, of which the following is a specification, reference being had to the accompanying drawing, forming part thereof, in which:

Fig. 1 is a perspective view of a peashooter showing my new design;

Fig. 2 is a front elevation of the peashooter hereof;

Fig. 3 is a rear elevation of the peashooter hereof.

I claim:

The ornamental design for a peashooter, substantially as shown.

ALVIN D. BLOOM.
